UNITED STATES PATENT OFFICE

THOMAS P. LEAMAN, OF HEMPSTEAD, NEW YORK, ASSIGNOR TO AMPHIBIONS, INC., OF GARDEN CITY, NEW YORK, A CORPORATION OF NEW YORK

TRIMMING DEVICE FOR AIRPLANES

Application filed March 4, 1931. Serial No. 520,020.

This invention relates to airplanes and more particularly to a trimming device therefor, and has for an object to provide an improved means for improving longitudinal stability control (rotation about a transverse horizontal axis Y) of an airplane in flight.

It is also an object of the invention to provide improved directional stability control (rotation about a vertical axis Z through the center of gravity) of an airplane.

Another object of the invention is to secure both of these controls in the same mechanism.

Still another object of the invention is to provide mounting means for two control members whereby the two controls may be simultaneously operated, and means whereby they may be individually adjusted with relation to each other.

With the foregoing and other objects in view the invention consists in certain novel features of construction, combinations and arrangements of parts as will be more fully disclosed in connection with the accompanying drawings.

In these drawings:

Fig. 1 is a side elevation of a conventional flying boat showing my invention applied thereto;

Fig. 2 is an end view on an enlarged scale looking forward;

Fig. 3 is a side elevation of one of my improved trimming air-foils or fins;

Fig. 4 is a transverse section thereof substantially on line 4-4 of Fig. 3;

Fig. 5 is a detailed perspective view showing the means for operating and adjusting the trimming air-foils or fins;

Fig. 6 is a detailed view of the hand control mechanism, partially in elevation and partially in section;

Fig. 7 is an elevation looking toward the left of Fig. 6; and

Figs. 8, 9, 10 and 11 are diagrammatical views looking aft showing different effects which may be secured with this improved trimming device.

In the drawings the hull of the conventional flying boat is indicated at 12 with any suitable type of wings 13 and the motor 14 op-

erating a propeller 15. Spaced rearwardly from the hull is the usual horizontal stabilizer 16 associated with the elevators 17 pivoted to swing about horizontal pivoted mountings 18, with the usual upright stationary fin or vertical stabilizer 19, and the vertical steering rudder 20 mounted to swing about an upright axis in the usual manner.

As is well known with change of loading the center of gravity will shift and therefore in order to maintain stability of the airplane in flight this change must be compensated for, but in place of the usual adjustment on the horizontal stabilizer for the purpose of maintaining longitudinal stability of the airplane in flight with change of airplane loading I have provided an improved means operable from the pilot's cock-pit for maintaining this stability and also providing directional stability or control of rotation about a vertical axis through the center of gravity.

I accomplish this by providing at a suitable distance either fore or aft of the center of gravity of the airplane trimming fins or airfoils which are inclined to the horizontal and extend laterally in opposite directions. The most convenient and effective position for mounting them is in the tail of the airplane and I have shown them in the drawings, as located under the horizontal stabilizer 16,

and on opposite sides of the vertical stabilizer or fin 19. These two trimming fins or airfoils are shown at 21 and 22, and each is mounted so as to turn about its longitudinal axis. It will be noted from Fig. 2, which

is a view looking forward, that each fin or airfoil is pivotally mounted on a support 23, and are inclined upwardly in opposite directions from their connections to the vertical stabilizer fin 19 to a point where they are connected to the underside of the horizontal stabilizer 16.

It will thus be evident that the two trimming members 21 and 22 extend laterally in opposite directions from the vertical central plane of the airplane and are inclined upwardly from a horizontal transverse line passing through their connections to the vertical stabilizer fin 19. These trimming elements 21 and 22 may be mounted on any suitable supports, but in order to simplify con-

struction and decrease the number of parts they are preferably mounted on the inclined struts usually provided between the under-sides of the horizontal stabilizer 16 and the lower edge portion of the vertical stabilizer 5. Thus the fins 21 and 22 are preferably mounted to turn about these struts which are indicated diagrammatically at 23, or they may themselves form the struts and thus take 10 the place of the usual struts, but in either case they are mounted to turn about longitudinal axes.

These trimming fins or airfoils 21 and 22 may be of any desired cross section but it is 15 preferable that they be made of airfoil section to reduce drag and render them more efficient, and they are also preferably inverted as indicated in Fig. 5 although not necessarily so. Rotation of these airfoils or 20 fins in one direction is resisted by elastic or shock absorber cords or springs 24 which are connected to fixed points on the horizontal stabilizer 16 at one end and at the other end are connected as shown at 25 to the airfoils 25 21 and 22 forwardly of their axes of rotation 23. These elements 24 therefore tend to turn 30 these members in one direction about their axes, that shown being in a direction to depress or lower their trailing edges 26. They 35 may be shifted in the opposite direction by a cable control leading to the pilot's cock-pit. Thus each one of these trimming elements is provided with an arm 27 to which is connected a cable 28 running over suitable guides 30 29 connected to bell cranks 30 pivoted at 31 to suitable supports 32. These bell cranks are connected by rod 33 on which is an arm 34 connected by a push rod 35 connected at 36 to a lever 37 pivoted at 38. This lever has 40 a hand grip 39 mounting for telescoping sliding engagement on the lever 37 and provided with a slot 40 for passage of a curved rack 41. A spring 42 tends to shift the grip 39 upwardly, and engage the lower walls of the 45 slot with the notches 43 in the rack and thus lock the lever in different adjusted positions. This lever will be located in the pilot's cockpit, and it will be evident that by merely depressing the grip 39 the handle will be unlocked to permit shifting of the lever either 50 forwardly or backwardly, and thus adjust the fins or airfoils 21 and 22 on their pivotal mountings. This will adjust the angular 55 relation of these fins both to the horizontal and vertical planes to secure the effects presently to be described. In each of the cables 28 is mounted a turn buckle 44 for adjusting the lengths of the cables and therefore the 60 relative positions of the members 21 and 22 may be independently adjusted with respect to each other. It will thus be evident that by manipulating the lever 37 the two fins or airfoils 21 and 22 are simultaneously shifted 65 about their pivotal mountings in the same direction and through the same angle, but by

manipulating the turn buckles 44 the angular position of either one about its pivotal mounting may be adjusted independently of the other.

The trimming fins 21 and 22 may be of any 70 suitable construction but as indicated above they are preferably of airfoil section, and may be of wood and metal framing 45 with ribs 46 of spruce or other suitable material bolted to metal torque tube 47 in order to 75 turn on the strut 23 or other mounting as desired, and the whole frame covered with suitable covering material such as fabric.

It will be evident that if the center of 80 gravity is shifted rearwardly then this may be compensated for to maintain longitudinal stability by means tending to lift the tail or depressing the nose of the aircraft. Thus as indicated in Fig. 8 the lever 37 has been 85 shifted to depress the trailing edges of the numbers 21 and 22 to equal angles of attack, the equal angles of attack being secured by proper adjustment of the turn buckles 34. As will be evident from the force diagram 90 of the vertical components 48 of the forces 49 of the fins are equal and positive. That is, upwardly and of course in the same direction, while the horizontal components 50 are equal and in opposite directions and toward 95 each other or inboard. The horizontal components therefore neutralize each other, but the vertical components being in the same direction tend to lift the tail.

If the center of gravity is shifted forwardly 100 then by manipulating the lever 37 in the opposite direction the trailing edges 36 may be raised as indicated in Fig. 9. In this view the trailing edges were lowered equal amounts to give equal angles of attack, but it will be evident that the vertical components 51 of the forces 52 are now downwardly but still in the same direction, while the horizontal components 53 are equal and in opposite directions but outwardly or outboard. Thus the horizontal components 105 neutralize each other, but the vertical components work together to depress the tail. 110

It will be evident that due to the inclination of the fins or airfoils 21 and 22 they are 115 capable of exerting a force which has both a horizontal and a vertical component. They therefore can be used not only for maintaining longitudinal stability of the airplane in flight with change in airplane loading as illustrated in Figs. 8 and 9, but they may also be used for directional stability control, that is, rotation about the vertical axis through the center gravity of the airplane. For this control the two fins or airfoils are moved in opposite directions, that is, the trailing edge of one is depressed or lowered and the other raised. This can be used to compensate for the effect of the spiral slip stream from the propeller on the tail fin or vertical stabilizer. Thus the effect of 120 125 130

the slip stream is to tend to force the tail fin toward the observer when looking as in Fig. 1 or that is, swinging the tail fin to the right when looking aft, then by adjusting the 5 turn buckles 44 one of the members 21 or 22 may have its trailing edge raised and the other depressed so that both horizontal components are in the same direction and help each other to overcome this effect on the tail 10 fin. Thus, in Fig. 10 the trailing edge 26 of the member 22 has been raised, while the trailing edge of member 21 has been depressed equal angles. Therefore, their horizontal 15 components 54 are equal and in the same direction and to the left while the vertical components 55 are in opposite directions. In Fig. 11 elements 21 and 22 have been adjusted to different angles. Thus the trailing edge of element 22 has been raised 20 while the trailing edge of element 21 has been depressed, but to a smaller angle than the element 22 has been raised. Thus both the vertical and horizontal components 56 and 57 are less than the vertical and horizontal 25 components 58 and 59 of the member 22, but the horizontal components 57 and 59 are in the same direction while the vertical components 56 and 58 are in opposite directions. All of these different effects and other 30 effects can be secured by proper manipulation of the turn buckles 44 and the lever 37.

This device is also effective to provide controllability of the airplane in a spin. Thus because members 21 and 22 are inclined at 35 an angle between the vertical and horizontal their effect or reaction from the air has horizontal components as well as a vertical component, as above described, which may produce in a spin a lifting force on the tail combined with a turning movement about the 40 rolling axis of the airplane, thus tending to turn the nose of the airplane downward and toward the inside of the spin. This is a very important feature as giving control in 45 a spin where ordinary elevators have no effect because in such a spin they are moving laterally and edgewise.

Having thus set forth the nature of my invention, what I claim is:

50 1. In an airplane having a tail portion including vertical and horizontal stabilizers, a fin extending between the vertical and horizontal stabilizers on each side of the vertical stabilizer, and each fin being inclined 55 at an angle between the vertical and horizontal, means mounting each fin to turn about its longitudinal axis, and means for adjusting the positions of the fins.

60 2. In an airplane having a tail portion including vertical and horizontal stabilizers, a pair of fins arranged one on each side of the vertical stabilizer and extending laterally and inclined upwardly in opposite directions therefrom, means mounting each fin to turn 65 about an inclined axis, and means for ad-

justing the positions of the fins about said axes.

3. In an airplane having a tail portion including vertical and horizontal stabilizers, a fin extending between the vertical and horizontal stabilizers on each side of the vertical stabilizer, and each fin being inclined at an angle between the vertical and horizontal, means mounting each fin to turn about an inclined longitudinal axis, means for simultaneously shifting the fins about said axes, and means for shifting the fins independently of each other.

4. In an airplane having a tail portion including vertical and horizontal stabilizers, a pair of fins arranged one on each side of the vertical stabilizer and extending laterally and inclined upwardly in opposite directions therefrom, means mounting each fin to turn about an inclined axis, means for simultaneously turning said fins about their axes, and means for turning the fins independently of each other.

5. In an airplane having a tail portion including vertical and horizontal stabilizers, inclined struts extending between the horizontal and vertical stabilizers on opposite sides of the latter and inclined in opposite directions, trimming fins mounted to turn about said struts, and means for adjusting the positions of the fins and retaining them in adjusted positions.

In testimony whereof I affix my signature.
THOMAS P. LEAMAN.
